UNITED STATES PATENT OFFICE.

JOSEPH MITCHELL, OF JERSEY CITY, NEW JERSEY.

DESIGN FOR A LAMP-SUPPORT OR SIMILAR ARTICLE.

40,646.

Specification for Design.

Patented Apr. 19, 1910.

Application filed January 27, 1910. Serial No. 540,463. Term of Patent 14 years.

To all whom it may concern:

Be it known that I, JOSEPH MITCHELL, a citizen of the United States, residing at Jersey City, in the county of Hudson and State of New Jersey, have invented a new, original, and ornamental Design for a Lamp-Support or Similar Article, of which the following is a specification, reference being had to the accompanying drawing, forming a part thereof.

The drawing is a perspective view of a lamp support or similar article showing my new design.

I claim:

The ornamental design for a lamp support or similar article as shown.

JOSEPH MITCHELL.
